UNITED STATES PATENT OFFICE.

MINNIE E. SILVERTHORN, OF CAYUGA, NORTH DAKOTA.

COLLAPSIBLE CRATE.

1,186,694.

Specification of Letters Patent. Patented June 13, 1916.

Application filed September 8, 1915. Serial No. 49,589.

To all whom it may concern:

Be it known that I, MINNIE E. SILVERTHORN, a citizen of the United States, residing at Cayuga, in the county of Sargent 5 and State of North Dakota, have invented certain new and useful Improvements in Collapsible Crates; and I do hereby declare the following to be a full, clear, and exact description of the invention, such as will enable others skilled in the art to which it applies 10 pertains to make and use the same.

This invention relates to new and useful improvements in collapsible crates, and the principal object of the device is to provide 15 a crate, which may be readily closed to occupy minimum amount of space when it is desired to return the same to the shipper.

Another object of the invention is to provide a crate which is constructed of sheet 20 metal or a similar material and which is so constructed as to fold into a small, light and compact bundle, which may be readily stored in such a manner as to occupy the minimum amount of space during reship- 25 ment.

A further object of the invention is to provide a crate which, when in its unfolded 30 position, forms a strong and rigid box for the shipment of articles, which may be easily broken.

With these and other objects in view, the invention consists in the novel combination and arrangement of parts which will be fully set forth in the following specification 35 and accompanying drawings, in which:—

Figure 1 is a perspective view of a crate constructed in accordance with this invention, Fig. 2 is a transverse sectional view on line 2—2 of Fig. 1, Fig. 3 is a longitudinal 40 sectional view on the line 3—3 of Fig. 1, Fig. 4 is a side elevation of the crate in a folded position, and Fig. 5 is a sectional view through the same in a folded position.

Referring to the drawings by characters of reference, the numeral 1 designates the bottom of the crate, provided along its front edge with the upturned flange 2, the upper edge of which is formed with the trough 3, 45 in which the lower edge of the front panel rests. Formed along one of the side edges of the bottom is an upturned flange 4 provided at its upper edge with a plurality of spaced hinge barrels 5. An upturned flange 50 6 is formed at the rear edge of the device, and this flange, like the flange 4, is formed

at its upper edge with a plurality of spaced hinge barrels. Formed on the side edge of the bottom opposite the flange 4 is a flange 8, which is of a height equal to substantially one-half of the height of the flanges 2, 4 60 and 6, and this flange 8, like the previous flanges, is formed with the hinge barrels 9.

Hingedly connected to the hinge barrel 4, by means of suitable hinge pins 10, are the hinge barrels 11 formed at the lower edge of the side wall 12. This side wall extends upwardly and carries near its upper edge the staple 13, the use of which will appear as the description proceeds. Hinged to the flange 8, by means of the hinge barrels 9, 65 is the side wall 14, which is provided with the hinge barrels 15, and these hinge barrels 15 split the spaces between the hinge barrels 9 so that their apertures align to receive the hinge pins 16. The upper edge of the wall 14 is provided with a plurality of hinge barrels 17, and hingedly connected thereto are the hinge barrels 18 of the top 19. The apertures in the hinge barrels 17 and 18 70 align to receive the hinge pin 20, and the top 19 is formed on its opposite edge with the hinge barrels 21 through which the hinge pin 22 extends and hingedly connects the locking plate 23 to the top. This locking plate 23 is formed with the hasp or extension 24 provided with the slot 25 through 75 which the staple 13 projects, when the device is in its unfolded position. A suitable hook 26 is secured to the plate 23 and hooks 90 through the staple 13 to hold the top closed, as illustrated in the drawings. The vertical edges of the walls 12 and 14 are formed with the outwardly extending bent back portions 27, the use of which will appear 95 as the description proceeds. These bent back portions form pockets in which the edges of the front and rear walls, which will be more fully hereinafter described, are held.

The edge of the top 19 is formed with the outwardly extending bent back portions 28 for the reception of the upper edge of the rear wall when the device is in its open position, as shown in Fig. 1.

Hingedly secured to the upper edge of the rear flange 6 is the rear wall 29, the edges of which are surrounded by the pockets formed by the outwardly extending bent back portions 27 and 28, and it will thus be 110 seen that a rigid connection is formed between the side, rear and top walls.

The front wall of the device, designated by the numeral 30, and consists of a single sheet of metal, the side edges of which are slideable in the outward extensions 27 at the front edge of the side walls and the lower edge of the front wall 30 engages in the pocket formed by the portion 3 of the flange 2. It will thus be seen that a close joint is formed along all of the edges of the device, and thus it will hold the same rigid and in rectangular form. A suitable handle 31 is secured to the top wall and forms a means by which the device may be transported while the flange 4 is provided with a handle to enable the device to be easily carried when in its folded position. The handle in the flange 4 is designated by the numeral 32, as illustrated in Fig. 4.

It will be apparent from the foregoing that in folding, the hook 26 is removed from engagement beneath the staple 30 and the top 19 is swung upwardly on its hinges, permitting the plate 23 to be swung inwardly to lie parallel to the top. The top is then swung downwardly to lie parallel with the side wall 14, and this side wall is then swung downwardly to lie parallel with the bottom 1. The front wall first being removed and placed on the bottom of the crate. The rear wall is then folded downwardly on top of the side wall 14, and the side wall 12 is then swung on its hinges downwardly on top of the rear wall, and it will be apparent that the device will be in its folded position and ready for transportation. The user may then grasp the handle 32, and it will be evident that the device will assume a small and compact bundle, which may be readily stored for shipment to the original sender, and the cost of returning the crates will be materially reduced.

While in the foregoing there has been shown and described the preferred embodiment

ment of this invention, it is to be understood that such changes may be made in the combination and arrangement of parts as will fall within the spirit and scope of the appended claims.

What is claimed is:—

1. A folding crate comprising a bottom, flanges formed at the edges of the bottom, a flange on one of said edges being substantially one-half of the height of the remaining flanges, a side wall hinged to the smallest flange, a side wall hinged to the opposite flange, a rear wall hinged to one of the remaining flanges, a top hinged to the first mentioned side wall, pockets formed at the edges of the side walls, and at the rear edge of the top for engaging the rear wall, and a removable front wall.

2. A folding crate of the character described comprising a bottom, upturned flanges formed at the edges of the bottom, one of the side flanges being substantially one-half the height of the remaining flanges, the two side flanges and the rear flange being formed with hinge barrels, a rear wall hinged to the rear flange, side walls hinged to the side flanges, a top hinged to the side flanges, a top hinged to the opposite side wall, a staple carried by the opposite side wall, a hasp hinged to the top and engaging the staple to lock the device in a closed position, pockets formed at the rear edges of the side walls and at the rear edges of the top wall for the reception of the edges of the rear wall, pockets formed on the front edges of the side walls, and a front wall removably held in the last named pockets.

In testimony whereof I affix my signature in presence of two witnesses.

MINNIE E. SILVERTHORN.
